1

The present invention relates to centrifugal machines for treatment of liquids on the countercurrent principle.

One main object of the invention is to provide a centrifugal machine having a centrifugal drum with inserted plates and being so constructed as to obtain a most possible sharp separation of the liquids in the drum.

When separating raw products and groups of substances into their individual constituents chemical industries make a difference between the processes of distillation, crystallization and the solvent extraction. The solvent extraction is characterized by two liquid currents made to counterflow each other and thus brought into close contact, with the view to making a third substance soluble in either liquid pass from the one to the other liquid. If it is therefore intended to extract from the liquid to be dealt with a substance dissolved in it, by means of solveng agents, the second liquid used as an extraction agent should be to the least possible extent soluble in the former liquid, and should be easily separable by the formation of layers. In consequence, the specific gravity of the second liquid should be different from that of the former liquid to be treated. The substance to be extracted must be soluble in the solvent agent to a greater extent than in the liquid to be treated, to obtain the desired effect. The more effective these qualities of the solvent agent are, the faster and in the result better the extraction will be, and the less solvent agent is used.

In the process of the solvent extraction it is known to pass two liquids on a spiral path in countercurrent through a centrifugal drum. In accordance with this method both liquids have to be fed under pressure into the centrifugal machine and contaminated liquids cannot be worked up owing to the fact that the solid substances are deposited on the spiral path and the liquid passage is clogged by them. These known centrifugal machines for carrying into effect a countercurrent treatment of liquids are complicated and expensive.

According to our invention the countercurrent treatment of liquids is executed by means of a centrifugal drum provided with inserted plates known per se, and these inserted plates are provided near their inner rims with a set of distribution channels positioned one above the other. From an inlet chamber in the drum a specifically heavier liquid is fed to the said distributing channels. Near their outer rims the plates are also provided with distributing channels which are fed

2

from another inlet chamber of the drum with a specifically lighter liquid. On account of this arrangement and by correspondingly connecting the discharging devices the result is obtained that the specifically lighter liquid is led through the package of plates from the outside to the inside, whilst the specifically heavier liquid flows through the package of plates in countercurrent from the inside to the outside. In order that this flow of countercurrent of both liquids can take place in the intermediate part of the plate package, between both groups of distributing channels the centrifugal pressure of the specifically heavier liquid from its level in its discharging chamber up to the distributing channels for the specifically lighter liquid near the outer rims of the plates must be smaller than the centrifugal pressure of the specifically lighter liquid from its level in its inlet or inlet chamber respectively up to the said distributing channels near the outer rims of the plates.

The devices for discharging both liquids from the centrifugal drum may be of different structure, the liquid may be either thrown out of the drum above overflow edges of disk shaped or otherwise shaped members or may be caught by a stripping device, such as a stripping disk.

The diameter or the distance of the said overflow edges from the axis of rotation of the centrifugal drum, or the outer diameter of the stripping disk respectively, can according to the invention be determined by the following equation or technical formula:

$$35 \quad \frac{v^2 - v_H^2}{2g} \cdot \gamma_H < \frac{v^2 - v_L^2}{2g} \cdot \gamma_L$$

This means:

v =the revolving speed of the liquids on the radius R , i.e. within the zone of the distributing channels near the outer rims of the plates;

v_L =the revolving speed of the specifically lighter liquid on its level in the inlet chamber, i.e. on the radius R_L ;

v_H =the revolving speed of the specifically heavier liquid on its level in the discharging chamber, i.e. on the radius R_H ;

γ_L =the specific gravity of the lighter liquid;

γ_H =the specific gravity of the heavier liquid;

g =the acceleration of the earth=9.81 m/sec.².

50 The revolving speeds being proportional to the radii belonging to them, from the above formula results in the following relation:

$$(R^2 - R_H^2) \cdot \gamma_H < (R^2 - R_L^2) \cdot \gamma_L$$

55 In case the inlet chamber for the specifically

lighter liquid being sealed against the stationary feeding channel for the specifically lighter liquid it is possible to feed this liquid to the centrifugal drum under overpressure. In this case there is no more a level of the specifically lighter liquid in the inlet chamber. The radius R_L becomes equal to zero, and to the centrifugal pressure of the liquid column the over pressure p is added by means of which the specifically lighter liquid is led into the drum, so that the formula for determining the diameter of the discharging devices for the specifically lighter liquid reads as follows:

$$(R^2 - R_H^2) \cdot \gamma_H < R^2 \cdot \gamma_L + p$$

The drawings show preferred embodiments of the invention.

Fig. 1 is a vertical section through the centrifugal drum of a countercurrent extraction centrifugal machine with an inserted plate package, and with the discharging devices with overflow edges for discharging the liquids,

Fig. 2 is a vertical section through a drum of similar structure, with stripping disks and a sealed connection between the inlet chamber for the specifically lighter liquid and the feeding channel for same,

Fig. 3 is a vertical section through a drum of similar structure, but with bent plates,

Fig. 4 is a vertical section through the drum of a countercurrent extraction centrifugal machine with an inserted package of plates divided in three parts, and

Fig. 5 is an enlarged fragmentary view of a portion of the intermediate set of plates as shown in Fig. 4.

In Figs. 1 and 2 the filling of the drum of the specifically lighter liquid is indicated by horizontal dotted lines, and the drum filling for the specifically heavier liquid by vertical dotted lines. The direction of flow of the liquids is indicated by arrows.

In Fig. 1 the centrifugal drum with its inner portion 3 is screwed on the driving spindle by a nut 2. The cover 4 of the drum is connected with the outer bottom portion 3a of the drum by means of a threaded ring 5. The plate package 8 is borne by a hollow conical member 9 inserted into the drum the lower wall of this member 9 acting as a distributor for the specifically lighter liquid and the upper part 9a of said member surrounding the inlet chamber 10 for the specifically lighter liquid. The inserted member 9 is provided with ducts 11 lying in a distance $=R$ from the axis of rotation of the drum, the ducts 11 leading to corresponding distributing channels 12 near the outer rims of the plates through which channels 12 the specifically lighter liquid enters into the plate package.

The specifically lighter liquid enters from the outside through the inlet pipe 13 into the inlet chamber 10, and the specifically heavier liquid enters through the feed pipe 14 into an inlet chamber 15 which is formed by a combined separating disc 16, 16a. The latter has in its lower portion ducts 17 leading to corresponding channels 18 of the plates 8 near their inner rims and forming a passage for the specifically heavier liquid to enter into the plate package.

The specifically heavier liquid flows along the inner side of the plates 8 towards the outside into the space 19 defined by the outer shell 3a of the drum whence the liquid passes through channels 20 into the discharging chamber 21 situated be-

tween the drum cover 4 and the separating disk 16. The specifically heavier liquid leaves the drum from the chamber 21 over the inner or overflow edge of the disk 6. This overflow edge 5 is positioned in a distance $=R_H$ from the axis of rotation of the drum. The revolving speed of the specifically heavier liquid on this spot is $=v_H$.

In countercurrent to the specifically heavier liquid the specifically lighter liquid flows along the outside of the plates 8 to the inside into the chamber 22 enclosed by the inner rims of the plates 8, and passes through channels 23 into the discharge chamber 24 whence it escapes out of the drum over the overflow edge of the separating disk 16.

The liquid level of the specifically lighter liquid in the inlet chamber 10 lies in a distance $=R_L$ from the axis of rotation. The revolving speed 20 of the specifically lighter liquid on this spot is $=v_L$.

The overflow edge of the disk 6 is situated in such a distance $=R_H$ from the axis of rotation of the drum, that the centrifugal pressure of the 25 specifically heavier liquid from its level in the discharging chamber 21 up to the distributing channels 12 of the plates 8 near their outer rims, in the distance $=R$ from the axis of rotation, is smaller than the centrifugal pressure of the specifically lighter liquid from its level in the inlet chamber 10 up to the distributing channels 14 near the outer rims of the plates 8, in the distance $=R$ from the axis of rotation.

In the distributing channels 12 and 18 both 35 liquids are mixed. In the middle part of the plate package, between the inner and the outer distributing channels 18 and 12 respectively, the liquids flow in counter current to each other and are still partially mixed with each other, while 40 in the inner and outer parts of the plate package 8 a sharp separation of the liquids takes place.

Instead of discharging the liquids from the drum over the overflow edges of the disks 6 and 16 the discharge may also be executed by 45 means of stripping disks the diameter of which is designated according to the above mentioned formulae.

As shown in Fig. 2 the connection of the stationary feeding pipe 26 with the inner part 25 of the distributor 27 surrounding the inlet chamber 28 for the specifically lighter liquid is executed by means of a gasket 29. The specifically lighter liquid is fed to the centrifugal drum under the overpressure p . The gasket 29 is fixed 55 in a known manner between the inner rim of the distributor 25 and the threaded ring 30 and is pressed against the inlet pipe 26 by the overpressure of the liquid in the inlet chamber 28. The inlet chamber 28 is completely filled with the specifically lighter liquid, so that owing to 60 this fact there is not even a free liquid level, but the over pressure p is already prevailing in the axis of rotation. The specifically lighter liquid flows through the distributing channels 31 lying in a distance $=R$ from the axis of rotation, and enters the plate package 32. Thence the liquid flows along the outer sides of the plates into the chamber 33 between the inner rims 65 of the plates and the upper portion 25 of the distributor 27 and thence into the discharge chamber 34 in which the liquid is caught by the stripping disk 35 and conveyed by same through channels 36 out of the drum.

The specifically heavier liquid flows through 70 channels 37 into the inlet chamber 38, thence to

the distributing channels 35 and through the plate package 32 into the space 40 at the periphery of the drum. From there the specifically heavier liquid passes channels 41 and flows into an upper discharge chamber 42 in which the liquid is caught by a stripping disk 43 and conveyed by same through channels 44 out of the drum. The liquid level where the specifically heavier liquid is caught by the stripping disk 43 lies in a distance $= R_H$ from the axis of rotation. The revolving speed of the liquid on this spot is $= v_H$.

The construction form of the centrifugal drum in Fig. 3 corresponds mainly with that in Fig. 2, only the plates, as shown in Fig. 3, are bent several times in such a manner that between adjacent plates arc shaped channels are formed. The breaks 41 and 43 are arranged between the distributing channels 45 and 46 of the plate package. On the operation of the centrifugal machine the currents of the specifically lighter and specifically heavier liquids are crossing each other in the distributing channels 45 and 46, as well as on the breaks 47 and 48 of the plates; so that the liquids are repeatedly mixed with each other and thereafter separated again from each other. By means of the repeated mixing of the liquids the extraction result is improved; and since in connection with an extraction in stages a sharp separation in the intermediate stages is less important than the repeated re-mixing, the output of the centrifugal machine is increased.

In the form of the centrifugal drum as illustrated in Fig. 4, the plate package comprises three sets, an inner set 71, an intermediate set 72 and an outer set 49 with distributing channels between these plate sets. The plates of the intermediate set 72 are several times bent in such a manner that between adjacent plates arc shaped channels are formed and that the upper and the lower sides of the plates are alternatively turned towards the axis of rotation of the drum. In the inner plate set 71 and in the outer plate set 49 a sharp separation of the liquids takes place, while in the intermediate plate set 72 only a comparatively rough separation of the mixed liquids is performed and a re-mixing of the separated liquids takes place at the breaks 50 and 51.

The specifically lighter liquid flows through the inlet pipe 52 into the inlet chamber 54 enclosed by the distributing tube 53, and through lower channels 55 to the vertical distributing channels 56. The specifically heavier liquid flows through a pipe concentrical to the inlet pipe 52 and through openings 57 into the inlet chamber 58 and thence into the distributing channels 59. Between the inner and outer distributing channels 59 and 56 respectively, and the intermediate plate set 72 are mounted perforated cylinders 69 and 70 by which the mixing of both liquids is improved. After having passed the openings in these cylinders 69 and 70 the liquids flow in countercurrent through the intermediate plate package. Thereafter the specifically heavier liquid flows through the outer plate set 49 and into the chamber 60 at the periphery of the drum, from there through channels 61 to the upper discharge chamber 62 from which the liquid escapes out of the drum by means of the stripping disk 63.

The specifically lighter liquid flows from the intermediate plate set 72 through the inner plate set 71 to the channels 64 and into the lower

discharge chamber 65 whence it is discharged out of the drum by the stripping disk 66. The stripping disk 63 must have such a large diameter that the centrifugal pressure of the specifically heavier liquid from its level in the discharge chamber 62 up to the distribution channels 56 between the outer and the intermediate plate package is smaller than the centrifugal pressure of the specifically lighter liquid from its level in the inlet chamber 54 up to the aforementioned distribution channels 56.

The Fig. 5 shows an enlarged portion cut out of the left side of the bent intermediate plate package, as shown in Fig. 4. The space between the plates is contracted at the breaks 50 and 51. The arrows marked in indicate the directions of the currents. The current of the specifically heavier liquid is indicated by small circles and the current of the specifically lighter liquid by small crosses. The specifically heavier liquid flows along that side of the plates which is facing the axis of rotation, to the outside; and the specifically lighter liquid flows along that side of the plates which is turned from the axis of rotation, to the inside. The lower part of the plate 67 and the upper part of the plate 68, as shown in Fig. 5, are alternately turned towards and away from the axis of rotation. At the breaks 50 and 51 the liquid currents are crossing each other, and by means of the contraction on these spots an especially intensive mixing of the liquids takes place.

What we claim is:

1. A countercurrent extraction centrifuge comprising a centrifugal drum having a multiple number of spaced-apart parallel discs positioned therein at an acute angle to the axis of rotation of the centrifuge, and dividing the interior of said drum into multiple liquid flow channels, said discs being positioned to leave the central and outer portion of the interior of said drum substantially disc-free, said discs having an inner and an outer series of openings collectively defining a first and a second liquid passage therethrough, said first liquid passage positioned from the top to the bottom of the interior of said drum near the central portion thereof, said second liquid passage positioned from the bottom to the top of the interior of said drum near the outer portion thereof, first conduct means positioned for passing a specifically heavier liquid into said drum downward through said first liquid passage and over the surfaces of said discs, second conduct means positioned for passing a specifically lighter liquid upward through said second liquid passage and over the opposite surfaces of said discs, whereby the two liquids are contacted at said first and second liquid passages and in said flow channels between said first and second liquid passages, first discharge means positioned for discharging specifically heavier liquid from said disc-free outer portion of the interior of said drum and second discharge means positioned for discharging specifically lighter liquid from said disc-free central portion of the interior of said drum.

2. Extraction centrifuge according to claim 1 in which said first and said second discharge means have liquid engaging portions for the discharge of the liquid so positioned from the axis of rotation of said drum that the centrifugal pressure of the specifically heavier liquid from said second liquid passages is smaller than the centrifugal pressure of the specifically lighter liquid from said first liquid passage.

3. Extraction centrifuge according to claim 2 in which said second liquid passage is positioned according to the following relation:

$$R < \sqrt{\frac{R_H^2 \cdot \gamma_H - R_H^2 \cdot \gamma_L}{\gamma_H - \gamma_L}}$$

in which R equals the distance of said second liquid passage from the axis of rotation of the centrifuge; R_H equals the distance of said first liquid passage from the axis of rotation of the centrifuge; γ_H equals the specific gravity of the heavier liquid; and γ_L equals the specific gravity of the lighter liquid.

4. Extraction centrifuge according to claim 1 in which said second conduct means is a stationary feeding pipe and an inlet chamber, said inlet chamber being centrally located in said drum, said feeding pipe being positioned for passing specifically lighter liquid into said inlet chamber and being sealed with a packing against the wall of said inlet chamber.

5. Extraction centrifuge according to claim 4 in which the liquid engaging portions of said first and said second discharge means are positioned at such a distance from the axis of rotation of said drum that the centrifugal pressure of the specifically heavier liquid from said second liquid passage is smaller than the sum of the centrifugal pressure of the specifically lighter liquid from the axis of rotation of the drum to said second liquid passage plus the pressure with which the specifically lighter liquid is fed to said drum.

6. Extraction centrifuge according to claim 5 in which said second liquid passage is positioned according to the following relation:

$$R < \sqrt{\frac{R_H^2 \cdot \gamma_H - R_H^2 + p}{\gamma_H - \gamma_L}}$$

in which R is equal to the distance of said second liquid passage from the axis of rotation of the centrifuge; R_H equals the distance of said first liquid passage to the axis of rotation of the centrifuge; γ_H equals the specific gravity of the heavier liquid; γ_L equals the specific gravity of the lighter liquid; and p equals the over pressure at which the specifically lighter liquid is fed into the drum.

7. Extraction centrifuge according to claim 1 in which said first discharge means and said second discharge means are each stripping disc means.

8. Extraction centrifuge according to claim 7 in which said first discharge means is a stripping disc in communication with the outer disc-free portion of the interior of said drum and said second discharge means is a stripping disc in communication with the central disc-free portion of the interior of said drum.

9. Extraction centrifuge according to claim 1 in which said first discharge means and said second discharge means each consist of members with an overflow edge over which the liquid to be discharged is thrown out of the drum.

10. Extraction centrifuge according to claim 1 in which said discs are bent at least once between said first and said second liquid passage so that a portion of both their upper and lower surfaces faces the axis of rotation of the drum.

11. Extraction centrifuge according to claim 10 in which there are restricting means provided on the discs at the bend for restricting the flow channels therebetween.

12. Extraction centrifuge according to claim 1 in which said multiple discs consist of at least one inner, one intermediate, and one outer set of discs, said first liquid passage being defined between said inner and said intermediate said discs, said second liquid passage being defined between said intermediate and said outer set of discs.

13. Extraction centrifuge according to claim 12 in which said intermediate set of discs are bent at least once so that a portion of both their upper and lower surfaces both face the axis of rotation of the drum.
